United States Patent Office.

E. P. GLEASON, OF NEW YORK, N. Y.

Letters Patent No. 96,909, dated November 16, 1869.

IMPROVEMENT IN LAMP-SHADE HOLDERS.

The Schedule referred to in these Letters Patent and making part of the same.

To all whom it may concern:

Be it known that I, E. P. GLEASON, of the city, county, and State of New York, have invented, made, and applied to use certain Improvements in the Construction of Shade-Holders for gas and other burners; and I do declare the following to be a full, clear, and correct description of my invention, reference being had to the accompanying drawings, making part of this specification, and to the letters of reference marked thereon, in which—

Figure 1 is a view of the ring to receive the wires of my shade-holder, one of the wires being removed.

Figure 2 is a view of one of the wires of my shade-holder.

Figure 3 is a top view of my shade-holder.

In the drawings, like parts of the invention are indicated by the same letters of reference.

The nature of the present invention consists in certain improvements, as more fully hereinafter set forth, in the construction of shade-holders for gas and other burners, the object of the invention being the production of a superior article of manufacture at less cost than heretofore.

The shade-holders most commonly employed consist of a ring, to which, at proper intervals, are soldered the straps, between which and the ring have been inserted the wires used to support the shade, which wires are, in turn, soldered in place.

My improved shade-holder consists of a ring of metal, A, provided with the straps *a*, which straps I punch or stamp up, by means of a male and a female die, out of the metal forming the ring A, so that they shall project beyond the face of the ring A, and receive the ends of the wires supporting, or intended to support the shade.

These wires B, for supporting the shade, are, prior to being bent into the required shape, submitted to the action of dies, by which the ends of the same, to be inserted within the straps, are flattened upon one side, while to the opposite side a half-round formation is given, as shown in fig. 2 of the drawings.

The wires B have their ends thus formed in order that, when placed within the straps *a*, the flat portion may bear upon the ring A, while the half-round portion accommodates itself to the incline of the strap, thus compelling the wires to retain their position, and preventing their turning, or being turned, after being received within the straps *a*.

After the wires B have been placed within the straps *a*, formed upon the ring A, the open spaces in the ring A, formed by punching out the straps, may be closed by solder, or in any convenient way.

It will be seen, that in forming the straps out of the metal constituting the ring, economy of metal is secured, while the ability to manufacture is greatly increased over the old plan, and that, by giving to the ends of the supporting-wires the flat and half-round formation, a more durable and superior article of manufacture is attained.

Having thus described my invention,

What I claim as new, and desire to secure by Letters Patent, is—

The combination of the wires B, having a flattened and half-round formation, with the ring A, provided with the straps *a*, when the same shall be constructed substantially as and for the purpose specified.

E. P. GLEASON.
